CRANK CASE CLEANER

Albert E. White, San Francisco, Calif.

Application July 11, 1932, Serial No. 621,976

2 Claims. (Cl. 210—134)

My invention relates to improvements in crank case cleaners, and it consists of the combinations, constructions and arrangements hereinafter described and claimed.

5 An object of my invention is to provide a crank case cleaner which will refine the crank case oil so that the oil will be restored to its original purity. The device is designed to be used with an internal combustion engine and to clean the 10 oil after the oil has done its work in the engine, and then to return the cleaned oil to the engine. The standard oil pump on the engine is sufficient to force the oil through the device. The clean oil, in returning to the engine under pressure, contacts with the various working parts of the 15 engine and cleans them. In time, this cleaning operation will remove all hydro-carbon, metallic substances, sand and other abrasives from the oil so that the oil will be in a pure state and all of 20 the parts of the engine, including the crank case, will be cleaned of impurities.

One of the advantages of the device lies in the fact that the crank case and other working parts of the engine are cleaned without the necessity 25 of removing the bottom of the crank case. The foreign matter in the engine is conveyed to the device by the oil, and the device retains the foreign matter. This foreign matter may be removed from the device without the necessity of 30 removing the device from the automobile.

The device makes use of a number of cells which carry a refining compound, and these cells may be changed in number so as to accommodate the device for engines having different quantities 35 of oil. For example, four cells or units are used for an automobile crank case containing eight quarts of oil. Two additional cells would be added to the device to adapt it to take care of a crank case holding twelve quarts of oil.

40 With this device in operation, it is not necessary to change the oil every one thousand miles, as is now the case with engines using only an oil filter. With the use of the present device, only sufficient oil would have to be added so as to make 45 up for any actual oil loss caused by leakage or burning.

Other objects and advantages will appear in the following specification, and the novel features of the device will be particularly pointed out in the appended claims.

My invention is illustrated in the accompanying drawings forming a part of this application, in which

55 Figure 1 is a diagrammatical view showing an

engine and the device operatively connected thereto;

Figure 2 is an enlarged side elevation of the device, portions being shown in section;

Figure 3 is a front elevation of the device; 60

Figure 4 is a perspective view of the inside of the top cell;

Figure 5 is a plan view of the inside of the bottom cell;

Figure 6 is a sectional view through a part of 65 the device showing the intake manifold; and

Figure 7 is a sectional view through another part of the device showing an exhaust manifold.

In carrying out my invention, I provide a bottom cell, indicated generally at A, a top cell indicated generally at B and an intermediate cell indicated generally at C. As many intermediate cells can be used as is necessary to take care of the quantity of oil to be cleaned. The bottom and top cells are the equivalent of one intermediate cell. 70

It is best to first describe the bottom cell, then an intermediate cell and then the top cell. The bottom cell is shown in Figure 5, and it will be noted that it has a base 1, with an upwardly-extending flange 2 integral with the top of the base. A bracket 3 is integral with the base and is used for supporting the device. A grill 4 is surrounded by the flange 2. 80

The base 1 has rear openings 5 for receiving 85 holding down bolts and front openings 6 and 7 for loosely receiving holding down bolts. The opening 6 also constitutes an intake manifold for oil, while the opening 7 constitutes an exhaust manifold for the oil. The base 1 has 90 an opening 8 leading from the grill 4, and an oil-return pipe 9, (see Figure 3), is connected to the base 1 so as to communicate with the opening 8. The base 1 also has an oil passageway 10 placing the opening 8 in communication with the exhaust 95 manifold 7. An oil inlet pipe 11, (see Figure 3), communicates with an oil inlet passage 12 in the base 1, and the passage 12, in turn, communicates with the intake manifold 6.

On top of the bottom cell A, I dispose an intermediate cell C. In Figure 2, I show three intermediate cells. Each of these cells is identical, and, therefore, a description of one will suffice. The cell C comprises a casting 13 having an agitating compartment 14 disposed between the 105 top 15 of the cell and an inwardly-extending flange 16. The flange may be of any shape desired, but I have shown the flange as being octagon in shape. The cell C has an opening 17 normally closed by a screw plug 18. This opening 110

gives access to the agitator compartment 14. A grill 19, similar to the grill 4 in the cell A, is carried by the top 15. A flange 20, similar to the flange 2, surrounds the grill 19. In other words, 5 the construction of the grill 19 and the flange 20 is identical to that of the grill 4 and the flange 2.

The top cell B has an agitating compartment 21 similar to the compartment 14 and a flange 22 10 similar to the flange 16. The cells C and B also have rear openings 5 and front openings 6 and 7, and when the openings 6 and 7 register with the same openings in the cell A, an intake and an exhaust manifold will be formed that extends 15 throughout the entire height of the device, regardless of the number of sections used.

In Figure 6, I show how each cell B and C is provided with a depending tubular extension 23 that forms a continuation for the intake manifold 6 in the section. The tubular extension 23 20 is received in a circular recess 24 in the top of the adjacent cell. A gasket 25 is placed in the recess 24, and when the two cells are clamped together by means of bolts 26 and nuts 27, a continuous liquid-tight passage for the incoming oil is provided. Gaskets 28 are placed adjacent to the 25 nuts 27 for closing the top and the bottom of the intake manifold. It will therefore be seen from this construction that oil entering the pipe 11, (see Figure 3), will first flow through the passage 12 30 and then will flow upwardly in the intake manifold 6 throughout all of the sections or cells, the oil surrounding the bolt 26.

Each of the cells B and C has an inlet passage-way 29, (see Figure 6). This inlet passage conveys the oil from the intake manifold to a spreader or baffle plate 30 that is inclined upwardly at a slight angle. The plate 30 is disposed in the agitator compartment 21, and similar plates are disposed in the agitator compartments 14. The 40 oil entering the compartments 14 and 21 is spread out through the compartment by means of the baffle plate 30 which is inclined upwardly at a slight angle. The oil will enter the agitator compartments of all of the sections B and C. In this 45 way, the oil is divided into different streams and each stream of oil is separately purified.

In the cell or section B, I dispose a screen 31, and this screen is supported by the flange 22. On top of the screen, I place a layer of filtering compound 32, such as fuller's earth. Beneath the flange 22, I dispose a gasket 33, and next to the gasket, I place a refining wafer. The wafer is composed of a top section 34 and a bottom section 35 of cloth, and between these two sections, I dispose wood pulp 36. The edges of the pieces of cloth 34 and 35 are cemented together so as to prevent the oil from passing out laterally through the edges. Beneath the wafer, I mount a second gasket 37, and this gasket rests upon the flange 60 20 of the next section or cell C. Between the wafer and the screen, I dispose a refining compound 38, such as a mixture of diatomaceous earth and oil.

The section C is provided with a screen 31, a 65 filter compound 32, a refining compound 38, a wafer consisting of the pieces of cloth 34 and 35 and the wood pulp 36 and the gaskets 33 and 37 in the same manner as the section B. Each section C is provided with the same number of parts 70 just enumerated. In this way, each stream of oil entering the agitator compartments 14 or 21 is purified.

After the oil has passed from the agitator compartment 21 down through the refining wafer, it 75 is received in the space 39 surrounded by the

flange 20 in the cells C, or the flange 2 in the cell A. The oil is guided by the grill 19, or the grill 4 back to an outlet opening. This opening is shown by the reference numeral 8 in the cell A, (see Figure 5), and by the reference numeral 40 in the cells C, (see Figure 7). The oil flows through the openings 40 into the exhaust manifold 7. This manifold is constructed in the same manner as the manifold 6 and like reference numerals will be given. The purified oil, in passing out through the exhaust manifold 7, surrounds the bolt 26 in the exhaust manifold.

This oil is then led to the outlet opening 10, (see Figures 3 and 5), and from there mixes with the oil passing out through the opening 8. The oil then enters the return pipe 9.

From the foregoing description of the various parts of the device, the operation thereof may be readily understood.

In Figure 1, I have indicated an internal combustion engine 41 with a crank case 42. I have shown the device as being secured to the dashboard 43. The bracket 3 of the cell A is secured to the dashboard, while a bracket 44 of the top cell B is likewise secured to the dashboard. The intermediate cells C are held in place by the bolts 26 and nuts 27. The inlet pipe 11 leads from the crank case 42 to the device, and the standard oil pump 45 of the engine is used for forcing oil through the inlet pipe. The purified oil passes 105 from the device through the return pipe 9, and this oil is conveyed back to the engine.

I have already stated how the oil from the crank case is divided into a number of streams and each stream is separately purified. This is accomplished by the oil first passing through the filtering compound 32, (see Figure 2). The pressure of the oil flowing through the pipe 11 is constantly changing, due to the varying speeds of the engine. This change of pressure causes the screen 115 31 to flex, and the screen therefore agitates the filtering compound 32 so as to mix the oil with the compound. The oil is then passed through the refining compound 38 and then passes through the refining wafer before it reaches the grill. 120 The oil, on reaching the grill, is purified and is cooled because the grill spreads the oil into a thin filament. The grill also acts as a catch basin for retaining any solids that might pass through the filtering and refining compounds. It will be noted 125 from Figure 5 that the grill walls form a zig-zag passage for the refined oil. This causes the oil to deposit any solids in the pockets formed by the staggered partitions rather than carry these solids back to the crank case. The oil then finds its way 130 to the exhaust manifold in the manner already stated and from the exhaust manifold, the oil passes back to the engine, through the return pipe 9.

It will be seen from this that the oil is constantly purified before it is returned to the engine. This pure oil will pick up foreign matter in the engine and will convey this foreign matter back to the cells and then the various compounds will remove the foreign matter from the oil. This 140 process in time will clean all of the working parts in the engine, including the crank case. From time to time, the plugs 18 are removed and the foreign matter is scraped from the top of the filtering compound where it has lodged. In this 145 way, the foreign matter is removed from the device rather than from the engine.

If the engine to which the device is connected uses a low-pressure oiling system, the device assumes the position illustrated in the drawings. 150

The oil will be carried to the top of each agitator compartment and will pass through the filtering and refining compounds by gravity. If the oiling system operates under high pressure, the device is inverted and the pressure of the oil is utilized in forcing the oil up through the compounds before it is led to the exhaust manifold.

Figure 3 shows a by-pass pipe 50 that connects the inlet pipe 11 with the outlet pipe 9. A spring-pressed ball check valve 51 is mounted in the pipe and permits flow of oil from the pipe 11 to the pipe 9 when the pressure of the oil exceeds a predetermined point. The check valve has a spring 52 that bears against the ball valve and against a spider 53. The spider is adjusted by the threaded rod 54 for placing the spring under the desired tension.

In practice the tension of the spring is set at about two pounds higher than the normal pressure of the oil in the lubricating system. If now the cleaning device should become clogged and prevent oil from passing therethrough, the check valve 51 would open and permit the by-passing of the oil. This would prevent any stoppage of the oil to the working parts of the engine and obviate any burning out of bearings and other parts.

While I have shown only the preferred form of my invention, it should be understood that various changes or modifications may be made

within the scope of the appended claims without departing from the spirit of the invention.

I claim:

1. In an oil purifier, a compartment, means for delivering a continuous flowing stream of oil to the compartment under varying pressures, an oil cleaning medium disposed in the compartment and designed to have all the oil pass downwardly therethrough, a flexible foraminous diaphragm supporting the cleaning medium, said diaphragm being supported at its edges of the sides of the compartment the varying pressures of oil causing the diaphragm to flex and to agitate the cleaning medium, whereby a more effective cleaning of the oil is accomplished as the oil passes through the medium. 80

2. In an oil purifier, a compartment, means for delivering oil to the compartment under varying pressures, an oil cleaning medium disposed in the compartment and designed to have the oil pass therethrough, and a flexible foraminous diaphragm supporting the cleaning medium, said diaphragm being supported at its edges by the sides of the compartment the varying pressures of oil causing the diaphragm to flex and to agitate the cleaning medium whereby a more effective cleaning of the oil is accomplished as the oil passes through the medium. 85 90 95 100
